RUBBER RAIL SEAT

Nelson K. Moses, Cuyahoga Falls, Ohio, assignor
of one-half to Paul A. Coley, Akron, Ohio

Application April 16, 1935, Serial No. 16,620

6 Claims. (Cl. 238—283)

This invention relates to rubber rail seats such as are used on the permanent ways of railroads between the rails thereof and the ties to which said rails are secured.

5 The chief objects of the invention are to effect more quiet and more comfortable passenger travel on railroads; to prolong the life of wooden ties by eliminating rail-wear thereon; to simplify the problem of ballasting the roadbed which heretofore permitted the ties to work up and down in the ballast; to keep the track true to gauge by preventing spreading of the rails; to equalize the 10 spring in the rails; to eliminate creeping of the rails and thereby obviate the use of anti-creepers; to reduce the tendency of the rail-ends to flow and batter in service; to cushion the rebound of a rail after a load has passed thereover, thereby eliminating the noise that accompanies movement of a rail against a spike-head, and 15 also preventing pulling of the spikes from the ties; to provide a rail-seat construction adapted to resist the action of the elements; to reduce the rocking motion of rolling stock, thereby eliminating breakage of freight and permitting faster travel with less vibration; and to provide a rubber rail seat that is easily and quickly applied to a rail. Other objects will be manifest as the specification proceeds.

Of the accompanying drawing,

20 Figure 1 is a vertical section through a track-rail and tie, and the improved rail seat assembled in operative relation therewith;

Figure 2 is a side elevation, on a larger scale, 25 of the improved rail seat;

Figure 3 is a plan view thereof; and

Figure 4 is a vertical section through an assembly that includes a rail seat comprising rubber and metal members.

30 Referring to the drawing, 10 is an ordinary wood railroad tie set in ballast 11, 12 is a standard track-rail, 13 is an improved rubber rail seat embodying the invention positioned beneath the rail 12 and resting upon the tie 10, and 14, 14 are the usual spikes that secure the rail and rail seat 35 to the tie.

The rail seat 13 is composed of molded, resilient rubber composition of high quality so as to resist aging and deterioration after exposure to the elements for periods of time as long as four or five 40 years. The thickness of the seat and its resilience are designed with a view to the conditions under which it is to be used, optimum results being obtained when there is a deflection under normal load of about one-eighth inch ($\frac{1}{8}$ ").

45 As is best shown in Figure 3, the rail seat 13 is

rectangular in shape, and has its top face formed with a transverse, undercut, rail-receiving groove 15, the portions of the structure overlying the undercuts of the groove constituting flexible lips or flanges 16, 16. The bottom of groove 15 is not 5 parallel to the bottom face of the seat structure, but is transversely tilted or canted, as shown, to provide the proper cant to the track-rail 12. Because of the canted arrangement of groove 15, the seat structure is thicker on the lateral marginal portion thereof that is adjacent the high side of said groove, and the respective lips 16 are of equal thickness. Since the rails 12 of a track are canted toward each other, it will be seen that 10 the thicker side of each rail seat will be outermost, whereby the seat is better able to resist normal lateral thrust of the rail and spreading of the rails is resisted. The groove 15 is the same width as the base flange of the rail 12, but its undercut portions are not of the same height as the 15 thickness of the marginal portions of the said base flange of the rail, as will be seen by reference to the broken line contour of a rail in Figure 2. The arrangement is such that when a rail is mounted in the rail seat, the lips 16 are flexed 20 upwardly, out of normal position, and put under tension, with the result that said lips normally press against the upper face of the said base flange, and moisture and grit are prevented from 25 penetrating between the rail and its seat.

30 The rail seat is formed with four spike holes 17, 17 adapted to receive respective spikes 14, said holes being disposed at the lateral margins of groove 15. Thus when the rail and rail seat are 35 spikied to a tie, the lateral margins of the base flange of the rail bear against the spikes, and the spike-heads overlie and somewhat compress the lips 16, as is most clearly shown in Figure 1. The arrangement is such that the lips 16 always remain in contact with the rail flange even when the latter is depressed under the normal load of 40 rolling stock passing thereover, said lips also serving to cushion the rebound of said rail flange, when the load is removed, so that there is no sudden impact against the spike-heads tending to 45 loosen the spikes in the tie. Moreover, the frictional contact between the rail flange and rail seat is of such strength as to prevent longitudinal movement or creeping of the rail, thus obviating the use of any other anti-creeping devices, and avoiding the detrimental effects of creeping.

50 Although the spikes on the outer side of the rail absorb most of the lateral thrust and prevent spreading of the rails, said spikes are given 55 strong lateral support by the thick rubber struc-

ture of the rail seat, which, being resilient, urges said spikes back to normal position in case they give under pressure. Furthermore, the yielding nature of the seat structure assures that lateral thrust against the spikes on one side of the rail will not be transmitted to the spikes on the opposite side of the rail. Experience has shown that the use of the improved rail seat practically eliminates loosening of the spikes.

10 The rubber rail seat protects the tie upon which it rests, and there is no such mutilation of the tie such as occurs when metal tie plates are used, or when the rail is applied directly to the tie. The seat is sufficiently flexible longitudinally of the groove 15 that it is easily flexed for the purpose of applying it to a rail at any point thereon. In this respect it is superior to other seats which are of such stiffness as to permit mounting upon a rail only from an end thereof. The seat is relatively simple in construction so as to be manufactured by a simple molding operation, its use results in substantial economy of maintenance to track-way and rolling stock, and it achieves the other advantages set out in the foregoing statement of objects.

15 The rail seat is especially useful at rail splices, in which situation the seat is slightly altered by the omission of the lips 16, and the spikes are inserted with their backs to the rail, this arrangement being necessitated by the presence of the usual splice bars. The rubber seat will build up a compression under one-eighth inch ($\frac{1}{8}$ ") deflection sufficient to support a normal load while the tie remains stationary, indicating that the impact between tie and ballast is practically nothing. On the other hand, in the absence of the rubber seat, the ties will have an up and down movement in the ballast of about one-quarter inch ($\frac{1}{4}$ ") under load. Thus the use 20 of the rail seat will reduce the strains on the splice bars and bolts, will reduce the impact between ties and ballast, and thus keep the joint in better surface. It will also considerably reduce the natural tendency of the rail ends to 25 flow and batter with service.

25 The embodiment of the invention shown in Figure 4 of the drawing is similar to that shown in Figures 1 to 3 except for the addition of a metal supporting plate 19 that is mounted between the tie 10^a and the rubber rail seat 13^a. The plate 19 is formed with a transverse groove or recess 20 in its top face, which recess is somewhat shallower than the thickness of the rail seat 13^a. The latter fits snugly within said recess 20, the arrangement being such that the plate 19 provides substantial lateral support to the inner and outer lateral faces of the rubber rail seat. The plate 19 is formed with spike holes 21 that are in registry with the spike holes

of seat 13^a when the latter is assembled on the plate, and which receive the respective spikes 14^a that secure the assembled structure and the rail 12^a to the tie 10^a. This embodiment of the invention provides greater lateral rigidity to the rail, but its use is not necessary except where the trackway is laid on a curve of 45° or less.

5 Modifications of the invention may be resorted to without departing from the spirit thereof or the scope of the appended claims.

10 What is claimed is:

1. A rail seat comprising a rectangular structure of resilient material formed with a transverse groove in its top face having undercut edges adapted to receive the base flange of a 15 rail, said undercut portions of the groove being of less height than the thickness of the flange structure received therein, and rail spike holes through the structure tangent to said groove at its region of greatest width.

2. A rail seat comprising a rubber rectangular structure formed with a transverse groove in its top face having undercut edges adapted to receive the base flange of a rail, said undercut portions of the groove being of less height than 20 those portions of the rail flange received therein.

3. In combination with a track rail, a non-metallic rail seat of resilient material underlying the base flange thereof, said rail seat being formed with integral, inherently resilient lips 30 normally urged against the top of said base flange by reason of their inherent resilience.

4. In combination with a tie and track rail, a resilient rail seat between the tie and rail formed with flexible lips that overlie the lateral marginal portions of the base flange of the rail, and rail spikes penetrating the said seat and extending into the tie beneath, the heads of said spikes bearing upon said flexible lips.

5. In combination with a tie, a track rail, and spikes for securing the latter to the tie, a rail seat consisting of a unitary structure of resilient material comprising a portion disposed between the tie and rail to furnish resilient support for the latter, a portion engaging the outer sides of 45 the spikes to laterally reinforce the same, and a portion disposed between the spike heads and the base flange of the rail constituting a cushion therebetween.

6. A rail seat comprising a rectangular resilient rubber structure formed with a rail receiving groove that extends transversely across its top face, said groove being canted with relation to the bottom face of the structure, the seat structure having a thicker marginal portion at 50 the high side of said groove than at the low side thereof.
